[57] CLAIM

The ornamental design for door hardware, as shown and described.

DESCRIPTION

FIG. 1 is a perspective view of door hardware showing my new design as embodied in a single pull;
FIG. 2 is a front elevational view thereof;
FIG. 3 is a top plan view, the bottom plan view being the mirror image thereof;
FIG. 4 is a right side elevational view thereof;
FIG. 5 is a rear elevational view thereof;
FIG. 6 is a left elevational view thereof;
FIG. 7 is a top plan view of a second embodiment of the design of FIG. 1 as embodied in paired pulls, the left pull being identical to FIG. 1 and the right pull being a mirror image thereof; and
FIG. 8 is a front elevational view of FIG. 7.
